(57) **CLAIM**

The ornamental design for a handle for a cable security device, as shown and described.

DESCRIPTION

FIG. 1 is a top perspective view of a handle for a cable security device showing our new design with the handle in the closed position;

FIG. 2 is a front elevational view thereof;

FIG. 3 is a rear elevational view thereof;

FIG. 4 is a top plan view thereof;

FIG. 5 is a left side elevational view thereof;

FIG. 6 is a right side elevational view thereof;

FIG. 7 is a top perspective view thereof with handle in the open position;

FIG. 8 is a front elevational view thereof;

FIG. 9 is a rear elevational view thereof;

FIG. 10 is a top plan view thereof;

FIG. 11 is a left side elevational view thereof; and,

FIG. 12 is a right side elevational view thereof.

The broken lines in the drawings represent unclaimed environmental subject matter.
